US00D802209S

(12) **United States Design Patent** (10) **Patent No.:** **US D802,209 S**
(45) **Date of Patent:** **** Nov. 7, 2017**

(54) **SPIRAL SHAPED TIP FOR USE IN ROLLED SMOKING ARTICLES**

(71) Applicants: **Joshua David Kesselman**, Vancouver (CA); **Ian Kobe**, Tempe, AZ (US)

(72) Inventors: **Joshua David Kesselman**, Vancouver (CA); **Ian Kobe**, Tempe, AZ (US)

(73) Assignee: **BBK TOBACCO & FOODS, LLP**, Phoenix, AZ (US)

(**) Term: **15 Years**

(21) Appl. No.: **29/564,392**

(22) Filed: **May 12, 2016**

(51) **LOC (10) Cl.** **27-99**

(52) **U.S. Cl.**

USPC **D27/194**

(58) **Field of Classification Search**

USPC D27/100, 101, 102, 162, 163, 164, 165, D27/166, 167, 168, 169, 170, 171, 172, D27/175, 180, 183, 184, 186, 187, 188, D27/189, 193, 194, 195; D22/116

CPC A24F 15/18; A24F 15/12; A24F 13/26; A24F 13/24

(74) Attorney, Agent, or Firm — Weiss & Moy, P.C.; Jeffrey D. Moy

(57) **CLAIM**

The ornamental design for a spiral shaped tip for use in rolled smoking articles, as shown and described.

DESCRIPTION

FIG. 1 is a perspective view of a spiral shaped tip for use in rolled smoking articles;

FIG. 2 is a front view of the spiral shaped tip for use in rolled smoking articles;

FIG. 3 is a rear view of the spiral shaped tip for use in rolled smoking articles;

FIG. 4 is a right side view of the spiral shaped tip for use in rolled smoking articles;

FIG. 5 is a left side view of the spiral shaped tip for use in rolled smoking articles;

FIG. 6 is a top view of the spiral shaped tip for use in rolled smoking articles; and,

FIG. 7 is a bottom view of the spiral shaped tip for use in rolled smoking articles.

1 Claim, 4 Drawing Sheets
